UNITED STATES PATENT OFFICE.

FRED P. GORIN, OF CHICAGO, ILLINOIS.

ATTACHMENT FOR TYPE-WRITING MACHINES.

No. 890,507.

Specification of Letters Patent. Patented June 9, 1908.

Application filed March 4, 1907. Serial No. 360,334.

To all whom it may concern:

Be it known that I, FRED P. GORIN, a citizen of the United States, residing at Chicago, in the county of Cook and State of Illinois, 5 have invented certain new and useful Improvements in Attachments for Type-Writing Machines, of which the following is a full, clear, and exact specification.

This invention relates to improvements in 10 attachments for typewriters and other similar machines of that class of attachments adapted to produce a plurality of original copies and now known usually as "multigraphs."

15 The invention in the present embodiment is shown applied to multigraph attachments of the general character illustrated and claimed in prior United States Patents No. 649,513 and No. 649,514, granted to me May 20 15, 1900, and in which attachments for the common forms of typewriters are shown having for their object the enabling of such 25 machines to make multiple copies, each of which copies is an original in that it is produced by means of a ribbon brought forcibly into contact with the surface of the paper by suitable type. The attachment as heretofore made consists primarily of a supplemental inking-ribbon and suitable means for 30 supporting and operating the same.

The supplemental ribbon is wound on 35 drums or reels and is operated by being wound on one of the drums or reels and discharged from the other after which the operation is reversed by shifting the supplemental ribbon in the opposite direction.

In devices of this character, great difficulty has heretofore been experienced in securing a proper and constant degree of tension on 40 the supplemental ribbon. To overcome this difficulty various expedients have been proposed and in my former patents I have shown spring actuated brakes in contact with the reels or drums for preventing the inertia 45 from carrying these parts beyond the required degree of movement, thus causing slack in the supplemental ribbon. In practice, however, I find that any form of friction device is not desirable by reason of the power 50 which is consumed in overcoming the resistance—the amount of power which may be used in operating a device of this character is necessarily limited,—and it is the primary object of this invention to provide improved

means for securing positive and complete control of the mechanism used in operating the supplemental ribbon and which is at the same time simple and economical in construction and capable of being operated with the minimum amount of power. It will be apparent, 55 however, that the invention may be used advantageously with many forms of inking ribbons and an object of the invention is to provide improved means for controlling the shifting mechanism of any form of inking ribbon 60 on typewriting machines and the like when such shifting mechanism embodies reels or drums on which the ribbon is alternately wound and unwound.

A further object of the invention is to provide improved means for reversing the movement of the reels or drums carrying an inking-ribbon.

A further object of the invention is to provide improved means for supplying ink to an 75 inking-ribbon.

To the attainment of these ends and the accomplishment of other new and useful objects, as will appear, the invention consists in the features of novelty in the construction, 80 combination and arrangement of the several parts hereinafter more fully described and claimed and shown in the accompanying drawings, illustrating an exemplification of the invention, and in which—

85 Figure 1 illustrates a plan view of a type writer carriage equipped with a multigraph attachment embodying the invention, and Fig. 2 is an end elevation taken approximately on line 2—2 Fig. 1. Fig. 3 is an enlarged vertical section on line 3—3 Fig. 1, with parts broken away to exhibit the construction in detail. Fig. 4 is a transverse sectional view on line 4—4 Fig. 1. Fig. 5 is an enlarged detail view of one of the reels or 90 drums for carrying the supplemental inking-ribbon and a portion of the adjacent controlling mechanism.

95 The attachment is in the drawings shown applied to a "Remington" typewriter, although it is obvious it may be equally well applied to other makes of machines. The lower part of the typewriter is not shown but the machine is, of course, provided with the usual main frame, set of keys, operating levers, type and ribbon or other inking device, all of which form no part of the present invention.

In the drawings the numeral 1 designates the carriage which is provided with the customary features of construction, which are well known and are therefore not particularly described. This carriage is provided with the ordinary printing platen or roll 2. Carried by suitable means to be hereinafter described is a supplemental inking-ribbon 3. When but a single copy is desired this supplemental ribbon 3 is thrown out of the way and not used, the single copy being made by use of the ordinary main ribbon which is mounted on the lower portion of the machine or any convenient location where it may be placed. The main ribbon is not illustrated in the drawings as it forms no part of the present invention. When two or more copies are desired the supplemental ribbon is employed and is placed between the sheets of paper in a manner which will be hereinafter described. To make one copy type bars are used in connection with the main ribbon of the machine, as just suggested, and when two copies are desired the additional or supplemental ribbon 25 is placed between the two sheets of paper, and type acting through the first sheet and through the supplemental ribbon makes the impression on the second sheet, it being understood of course that the raised surface 30 of the type makes a corresponding impression in the first sheet and the supplemental ribbon and thereby is enabled to leave a similar mark upon the second sheet, with which the raised portion of the ribbon contacts by reason of the pressure of the type. If the supplemental ribbon be placed immediately between the two sheets it will be apparent that not only two impressions will be made as described but there will also be 35 a third impression on the back of the first sheet, which is not only of no use, because it is a reverse impression, but it also mars the appearance of the first sheet. To avoid this defect, the side of the ribbon next the back 40 of the first sheet may be covered by protecting material, either integral with the ribbon, or, what is more preferable, a removable protecting strip, which may be of the same length as the supplemental ribbon 3, and be 45 manipulated with it in the manner shown and described in my prior patent No. 469,514, to which reference has already been made. This protecting strip is not illustrated herein, for the reason that it forms 50 no part of the present invention. If three copies are desired, a third sheet of paper (preferably thinner than the other two sheets and in lieu of the protecting strip just mentioned) is placed between the supplemental ribbon and the first sheet, and in this manner the third sheet will receive an impression upon its back of a reverse character, but which may be read correctly when looking from the front or other side of the sheet. 55 It is obvious that the supplemental ribbon 60

may be of any convenient size and shape, according to the occasion or machine on which it is employed, and may be mounted for shifting in many different ways. However, the construction shown is the most advantageous known to me, and is the one to which the invention is particularly applicable.

On the end members of the carriage frame 1, upright supporting members 4 and 5 are secured. Journaled in the upper ends of members 4 and 5 is a suitable shaft, which protrudes at its ends through the members 4 and 5, and on the outer ends of which is carried the reels or drums 6 and 7. The ribbon 3 is attached at its ends to the drums 6 and 7, and is deflected downwardly from both of the drums, in order that it may traverse the entire length of the carriage and consequently the entire length of the platen or paper feed roll 2. This deflection of the ribbon and guiding of the same in its relation to the platen, may be accomplished by suitable guides 8 and 9 supported at the lower extremity of the depending members 10 and 11. The construction of these guides is not described in detail, since they form no part of the present invention, and since they are described and shown in detail in my patent last referred to. It will be apparent, however, by referring to the illustrations, particularly Figs. 2 and 3, that these guides 8 and 9 should be formed so that they will give the ribbon 3 a quarter turn at the same time that it is deflected at right angles in order to permit it to pass adjacent to the surface of the platen, and at the same time be parallel with such surface. These guides are also provided with suitable means, as the hooks 12 and 13 by which wires or cords, one strand on each side of the supplemental ribbon may be held taut between the guides. These wires or cords on each side of the supplemental ribbon 3, one of which is designated in drawings (see Fig. 3) by the numeral 14, are preferably of a size somewhat greater in diameter than the thickness of the ribbon, and thus serve as a protective means for the ribbon when the paper is shifted, preventing the paper from coming into such immediate contact with the ribbon, as would cause it to be deflected from its proper position, or to smut the paper by reason of such contact. This feature of the device is also shown and described at greater length in my prior patent last mentioned, and forms no part of the present invention.

The guides 8 and 9 are preferably pivotally connected to the lower ends of members 10 and 11 and they may be held or caused to assume any desired position in relation to the members 10 and 11, by having suitable upwardly extending branches 8^a and 9^a in contact with the guiding flanges 4^a and 5^a on the lower extremities of the stationary members 130

- 4 and 5, as it will be seen by reference to Fig. 3 that these members are shown extending below the carriage frame. In order that the guides 8 and 9 may be adjustably mounted, the members 10 and 11 are secured near their upper extremities to the same axis on which the drums 6 and 7 are carried. The construction of this axis carried by the upright supports 4 and 5 will now be described.
- 10 The outer sleeve 15 is journaled in the uprights 4 and 5, having its ends extending beyond its points of support in such members, a distance sufficient to receive depending members 10 and 11, which are firmly secured to it, in order that both depending members will move simultaneously, thus causing the supplemental ribbon guides 8 and 9 to have corresponding movements for preserving a proper alinement of the supplemental ribbon.
- 15 Within the sleeve 15 is a second sleeve 16, having its outer extremities extending beyond the ends of the sleeve 15, and on the outer ends of which the drums 6 and 7 are carried. Within the sleeve 16 is the longitudinally movable rod or shaft 17, having its ends extending somewhat beyond the extremities of the sleeve 16, and provided with suitable enlarged portions 18 and 19, carrying the inwardly projecting lugs 20 and 21.
- 20 Drums or reels 6 and 7 are journaled on sleeve 16 so as to rotate thereon and are preferably held against lateral movement by suitable pin or screw 22 adapted to coöperate with a corresponding annular groove 23 in sleeve 16. It will be apparent that the purpose of the longitudinally movable rod 17 and the end members carried thereupon is to lock the reels or drums 6 and 7 alternately to rotate with the rod 17.
- 25 The rod 17, however, while permitted to have longitudinal movement in relation to sleeve 16 is nevertheless secured against rotation in relation to this sleeve by suitable means as threaded screw or pin 24 adapted to coöperate with the longitudinal groove 25 in rod or shaft 17. The exterior surface of the members 18 and 19 at the ends of rod or shaft 17 are formed of convenient size and shape for the operator and preferably have 30 their outer surfaces knurled as illustrated (see Fig. 3). In the typewriter carriage of the construction to which the invention is applied in this embodiment a suitable operating lever 25 is provided. This lever is in the shape of a bell crank and is pivoted to carriage frame 1. It has an upwardly extending branch 25^a to which the gravity pawl 26 is pivoted and adapted to coöperate with the ratchet wheel 27 on paper feed roll or platen 2.
- 35 By this construction when the lever 25 is moved on its pivotal mounting by the operator pawl 26 coöperating with ratchet 27 operates the platen or roll. Near the upper extremity of the branch 25^a a second gravity pawl or rack is pivoted designated by the num- 40

- meral 28. This member is provided with a plurality of teeth 28^a adapted to coöperate with the teeth of the ratchet wheel 29 which is fixed to sleeve 16 by a suitable spline or key 30 or in any other suitable manner. Thus it will be seen that when the mechanism for shifting the feed roll or platen is operated the ratchet 29 and the sleeve 16 will be correspondingly rotated. It will be apparent that when the ribbon is being wound on to one of the drums 6 and 7 the other of the drums must rotate in the opposite direction in order to give off a corresponding quantity of ribbon. To secure this result one of the reels or drums 6 and 7 must at all times be left free to rotate independently of sleeve 16. This is accomplished by the construction already described for it will be seen that when one of the inwardly extending lugs or pins 20 and 21 is in contact with the corresponding depressions 20^a and 21^a in the drums 6 and 7 the other of such engaging pin or lug must be disengaged thus freeing its corresponding reel or drum. From this description it will be seen that the ratchet 29 and the sleeve 16 rotate constantly in the direction indicated by the arrow in Fig. 2 which is also in the direction of the constant rotation of the platen or feed roll. When the rod or shaft 17 is in position shown in Fig. 3 the drum 6 will be locked in the manner described to the sleeve 16 and will be rotated thereby winding the ribbon 3 upon it, while at the same time the drum 7 will be free to revolve and the ribbon will be taken from it. On the other hand when the ribbon is exhausted from drum 7 the direction of its movement is shifted by the operator who disconnects the drum 6 and locks the drum 7 to the sleeve 16 all of which is accomplished by shifting the rod 17 thus engaging the lug or pin 21 with its corresponding depression 21^a in drum 7 and at the same time disconnecting lug 20 from its corresponding depression 20^a in drum 6. In this manner the supplemental ribbon may be continuously operated as long as desired. This constant shifting process accomplishes a beneficial result in the use of inking-ribbons well known and understood by those versed in the art. In a ribbon of this character, however, it is sometimes desirable that means be provided for replenishing the same with ink. To accomplish this purpose the following provision is made. A suitable receptacle is secured to one or both of the depending guide supports 10 and 11 as illustrated by the numeral 31. This member as illustrated is cylindrical in form and in length somewhat greater than the width of the ribbon 3. It is placed in the path of the ribbon preferably deflecting it slightly as it comes from the drums. A small distributing roller 32 is also pivoted adjacent to the member 31 and serves as a convenient guide for the ribbon particularly

when provided with the loop guide pivot 32^a. The member 31 is provided with a suitable inner cavity to be filled with ink and the ink is preferably retained therein by suitable sponge substance as felt and the like as designated by the numeral 31^a. The wall of the receptacle adjacent the distributing roller 32 is broken away at 31^b and the distributing roller 32 is so mounted in relation to this opening that it is in constant contact with the ink retaining substance in the cavity 31^a. By this construction the ribbon 3 is constantly fed with a small supply of ink which is distributed in such a manner that the ribbon is not overfed.

Reference has already been made to the difficulty heretofore experienced in securing a proper and constant degree of tension on the supplemental ribbon. It will be apparent from the above description of the manner in which the supplemental ribbon is shifted between the drums or reels 6 and 7 by the ratchet pawl which acts on the toothed wheel 29 that when the ribbon has been wound so that one of the drums is filled and the other empty and the direction of shifting of the ribbon reverses the full drum by reason of its excessive weight due to the presence of practically the entire ribbon wound thereupon will on account of its inertia have a tendency to continue giving off the ribbon when once its movement has begun thus causing the ribbon to become slack and leave the printing line so that the type will fail to strike it and no copy be made.

The mechanism by which the reels or drums are controlled with a variable movement corresponding to the variable movements of the reels or drums due to the winding and unwinding of the ribbon thereon will now be described.

Pinions 33 and 34 are formed integral with drums 6 and 7 or are attached thereto in any suitable manner. Pinion 33 meshes with a similar toothed pinion 35 which is mounted on shaft 36 journaled to rotate in suitable bearings near the upper extremity of members 4 and 5. This shaft 36 may be secured against lateral movement by suitable collars 37 and 38 bearing against members 4 and 5 and this shaft terminates immediately after passing through the member 5. The drum 7 likewise carries a pinion 39 meshing with a similar pinion 40 secured to one end of shaft 41. This shaft, like 36, is also journaled to rotate near the upper extremities of members 4 and 5 but is separated some distance from the shaft 36 preferably as shown in drawings on the opposite side of the sleeve 16 although the arrangement of the members 36 and 41 may be varied without detracting from the operation of the device or departing from the purpose or spirit of the invention. The shaft 41 is likewise secured against longitudi-

nal movement by suitable collars 42 and 43 adjacent the members 4 and 5. The conical rollers 44 and 45 are carried on shafts 36 and 41. The roller 44 being preferably fixed thereto by any suitable means as for example a threaded pin or screw 46 while the roller 45 is loosely journaled on shaft 41 but is caused to rotate therewith by the helically wound spring 47 surrounding shaft 41 and secured at one end thereto by suitable means as collar and set screw indicated by the numeral 48 while the other end of the spring is secured to one end of conical roller 45. This construction permits the conical roller 45 to have a limited amount of movement both rotatably and longitudinally on the shaft 41 under the elastic control of the spring 47. A suitable flexible member preferably a stout fishcord or the like as indicated by the numeral 49 is attached at both its ends to the large end of the conical rollers 44 and 45 as indicated at 50 and 51. It will be observed that the conical rollers 44 and 45 are duplicates in size and construction but that their position with reference to their ends are reversed on the shafts 36 and 41. The shape of these conical rollers is determined by the variation in the movements of the drums or reel 6 and 7 and the ribbon 3 which is due to the fact that the size of the roll or drum over which the ribbon is wound constantly varies as the amount of ribbon on the drum or reel increases or diminishes.

The conical drum or roller 45 is loosely mounted on shaft 41 and held in normal position by the helical spring 47 in order that it may be free to move longitudinally on shaft 41 which is desirable as it permits the member 45 to constantly adjust itself so that the cord 49 may be given off and taken on these conical rollers at points approximately opposite each other which prevents improper wrapping of the cord thereupon. The operation of this controlling mechanism is as follows: When the reel or drum 6 is locked to rotate as shown in Figs. 1 and 3 the movement of the feed roll shifting lever 25 imparts rotary movement to sleeve 16 through ratchet pawl 28 and ratchet wheel 29 which movement is imparted to reel 6 thereby winding the supplemental ribbon 3 upon it and taking the ribbon from drum 7 which is free to rotate on sleeve 16. When drum 6 rotates to take on the ribbon it will be seen that shaft 36 will be rotated through the pinions 33 and 35 and the cord 49 will be unwound from drum 44. At the same time the supplemental ribbon 3 in winding off drum 7 will cause it to rotate in the opposite direction from the direction of rotation of drum 6 and this movement will be imparted to shaft 41 through pinions 39 and 40. Rotation of shaft 41 will be imparted to conical drum 45 through the helical spring 47, which will ro-

tate in the direction necessary to wind the cord 49 upon it. As rotation of drum 6 continues its size increases by reason of the amount of the ribbon wound upon it and consequently the tape or ribbon 3 is wound in increasing ratio which imparts an increasing degree of movement to drum 7. It will be seen that this increased movement on the part of drum 7 is compensated by the decreasing size of the drum 45 as the winding of the tape on drum 6 increases while the amount of cord 49 given off the conical drum 44 increases in the desired ratio by reason of the conical shape of the drum. By this construction it will be seen that if the tension of the ribbon as it leaves drum 7 has a tendency to cause the drum to rotate by reason of inertia after the movement of drum 6 stops, such movement will be checked by reason of the fact that when drum 6 stops it positively stops the rotation of shaft 36 and the conical drum 44 which through cord 49, conical drum 45 and its elastic connection to shaft 41 will check the movement of shaft 41 and consequently the movement of drum 7 which is positively connected to shaft 41 through pinions 39 and 40. When the supplementary ribbon 3 is entirely unwound from drum 7 and is wound upon drum 6 the operator shifts the direction of movement of the supplementary ribbon by sliding the rod 17 longitudinally so as to engage lug or projection 21 with its corresponding depression 21^a in drum 7 thus causing the drum 7 to be rotated positively by the rotation of the sleeve 16 and the ratchet 29. When shaft 17 is shifted to lock the drum 7 the drum 6 is free to rotate on the shaft 16 by reason of the disengagement of the lug 20 with its corresponding depression 20^a in drum 6. As the operation of the machine proceeds it will be seen that the supplementary ribbon 3 will now be wound upon the drum 7 and the drum 6 will be rotated in the opposite direction to give off the ribbon. It will also be seen that the controlling mechanism will now be operated with respect to drum 6 as the cord 49 will now be wound upon the conical drum 44 and taken from the conical drum 45 and when the inertia of the drum 6 would give it a tendency to travel beyond the movement of the drum 7 such movement will be checked by reason of the fact that cord 49 will be given off the drum 45 to the drum 44 only as the drum 45 is rotated by reason of its positive connection through shaft 41, pinions 40 and 39, with the drum 7.

In the foregoing specification I have described the preferred form of embodiment of my invention, but it is obvious that many changes and variations may be made by those skilled in the art without departing from the principle of the invention.

In order that the invention might be fully

understood the details of an embodiment 65 thereof have been thus specifically described but

What I claim is:—

1. In a typewriter or similar machine, the combination with an inking ribbon, of reels 70 or drums on which the ribbon may be wound and controlling means coöperatively related to the reels or drums and having a variable movement corresponding to the variable movements of the reels or drums. 75

2. In a typewriter or similar machine, the combination with an inking ribbon, of reels 80 or drums on which the ribbon may be wound and positive controlling means coöperatively related to the reels or drums and having a variable movement corresponding to the variable movements of the reels or drums determined by the winding of the ribbon thereupon.

3. In a typewriter or similar machine, the combination with an inking ribbon, of reels 85 or drums on which the ribbon may be wound and controlling means coöperatively related to the reels or drums and having a predetermined variable movement corresponding to the variable movement of the reels or drums. 90

4. In a typewriter or similar machine, the combination with an inking ribbon, of reels 95 or drums on which the ribbon is adapted to be wound, and compensating controlling means, embodying rollers or drums and flexible means adapted to be wound thereupon, coöperatively related to the said reels or drums on which the ribbon is adapted to be wound.

5. In a typewriter or similar machine, the 100 combination with an inking ribbon, of reels or drums on which the ribbon is adapted to be wound, and controlling means embodying rollers or drums and flexible means adapted to be wound thereupon, coöperatively related 105 to and having a variable movement corresponding to the variable movement of the reels or drums, on which the ribbon is adapted to be wound.

6. In a typewriter or similar machine, the 110 combination with an inking ribbon, of reels or drums on which the ribbon may be wound, and compensating means for controlling the reels or drums.

7. In a typewriter or similar machine, the 115 combination with an inking ribbon, of reels or drums on which the ribbon may be wound, and positive compensating means for controlling the reels or drums.

8. In a typewriter or similar machine, the 120 combination with an inking ribbon, of reels or drums on which the ribbon is adapted to be wound, and controlling means, embodying drums provided with conical winding portions on which a flexible member or cord is 125 adapted to be wound, coöperatively related to each of the said reels or drums.

9. In a typewriter or similar machine, the

combination with an inking ribbon, of reels or drums on which the ribbon is adapted to be wound, and controlling means co-operatively related to said reels or drums and embodying winding drums provided with conical winding portions and a flexible member connected at its ends to the conical winding portions.

10. In a typewriter or similar machine, the combination with an inking ribbon, of reels or drums on which the ribbon is adapted to be wound, and controlling means co-operatively related to said reels or drums and embodying winding drums provided with conical winding portions having their corresponding surfaces oppositely disposed in relation to each other and a flexible member connected at its ends to the conical winding portion.

20 11. In a typewriter or similar machine, the combination with an inking ribbon, of reels or drums on which the ribbon is adapted to be wound, rotatable shafts operatively connected to each of said reels or drums, conical winding drums on each of said rotatable shafts and a flexible member connected to the conical winding drums.

12. In a typewriter or similar machine, the combination with a supplemental inking ribbon, of reels or drums on which the supplemental ribbon is adapted to be wound, and compensating means for controlling the reels or drums.

35 13. In a typewriter or similar machine, the combination with a supplemental inking ribbon, of reels or drums on which the supplemental ribbon is adapted to be wound, and positive compensating means for controlling the reels or drums.

40 14. In a typewriter or similar machine, the combination with a supplemental inking ribbon, of reels or drums on which the supplemental inking ribbon is adapted to be wound, and controlling means, embodying drums provided with conical winding portions on which a flexible member or cord is adapted to be wound, co-operatively related to the said reels or drums.

50 15. In a typewriter or similar machine, the combination with a supplemental inking ribbon, of reels or drums on which the ribbon is adapted to be wound, and controlling means co-operatively related to the said reels or drums, embodying rotatable shafts operatively connected to said reels or drums, a conical winding drum fixed to one of the shafts, a conical winding drum loosely mounted to rotate on the other of the said rotatable shafts, a helical spring encircling the last 60 said shaft and attached at one end thereto and secured at its other end to the said loosely mounted winding drum, and a flexible member secured at its ends to the said conical winding drums.

16. In a typewriter or similar machine, the combination with a supplemental inking ribbon, of reels or drums on which the supplemental inking ribbon is adapted to be wound, rotatable shafts operatively connected to each of said reels or drums, a conical winding drum secured to one of the rotatable shafts, a conical winding drum journaled on the other of said rotatable shafts and secured thereto by elastic means, and a flexible member connected to the said conical winding drums.

17. In a typewriting machine, the combination of a paper feed carriage, brackets mounted at the ends thereof, a shaft mounted in said brackets, auxiliary ink ribbon spools carried on said shaft, and means co-operatively related to the said shaft and to the auxiliary spools whereby when one of the said spools is locked to rotate with the shaft, the other is free to rotate thereon.

85 18. In an attachment for typewriters and similar machines, the combination with a cylindrical platen, and mechanism for feeding the paper over the type line on such platen, of a supplemental ribbon, reels or drums on which said ribbon is adapted to be wound, a rotatable member on which the reels or drums are carried, mechanism for operating the said cylindrical platen, means by which the said rotatable member is operated 90 by the said platen operating mechanism, and means co-operatively related to the rotatable member and to the reels or drums whereby when one of the reels or drums is locked to rotate with the said member the other is free 100 to rotate.

19. In a typewriter or similar machine, the combination with a paper feed carriage, and a cylindrical platen, of a supplemental inking ribbon, reels or spools on which the said supplemental inking ribbon is carried, a rotatable shaft supporting said spools or reels, mechanism adapted to impart a synchronous movement to the said cylindrical platen and to the said rotatable shaft, and locking 110 means co-operatively related to the rotatable shaft and to the said reels or drums whereby when one of the reels or spools is locked to rotate with the shaft, the other is free to rotate thereon.

115 20. In a typewriter or similar machine, the combination with a paper feed carriage, and a cylindrical platen, of a supplemental inking ribbon, a rotatable shaft supported on the said paper feed carriage being journaled 120 therein approximately parallel with the said platen and having the extremities thereof extending beyond the ends of the platen, reels or spools adapted to carry the said supplemental inking ribbon secured to the extremities of the said rotatable shaft, mechanism adapted to impart a synchronous movement to the said cylindrical platen and to the

said rotatable shaft, and locking means co-operatively related to the rotatable shaft and to the reels or drums whereby when one of the reels or spools is locked to rotate, the 5 shaft, the other is free to rotate.

In testimony whereof I have signed my name to this specification, in the presence of

two subscribing witnesses, on this 28th day of February A. D. 1907.

FRED P. GORIN.
